STOKER GRATE BLOCK

Herbert E. Preston, Philadelphia, Pa., assignor to American Engineering Company, Philadelphia, Pa., a corporation of Pennsylvania

Original application March 22, 1928, Serial No. 263,900. Patent No. 2,081,067, dated May 18, 1937. Divided and this application February 12, 1936, Serial No. 63,544

12 Claims. (Cl. 110—44)

This invention relates to lower grates for stoker furnaces, and more particularly to the grate blocks employed on such devices.

One object of the present invention is to provide a generally improved grate block construction which is adapted to be secured to the supporting framework without the use of bolts, keys, or other separate fastening means, the parts being such that they may be easily renewed with minimum disturbance to adjacent portions of the stoker.

Another object is to provide an improved grate block construction having means provided thereon for distributing the air into the furnace, and also having cooling fins provided thereon, whereby the blocks are maintained relatively cool during operation of the furnace.

Other objects of my invention will become apparent more fully hereinafter when taken in connection with the accompanying drawings herein.

Fig. 1 is a longitudinal sectional view taken through the lower end of a stoker furnace, showing the grate blocks comprising the present invention assembled upon the supporting structure 25 of the lower grate.

Fig. 2 is an enlarged detail longitudinal sectional view of the stationary lower grate structure and the anti-friction supporting means for the lower end of the steel supporting beams, the sectional plane being taken on line 2—2 of Fig. 3.

Fig. 3 is a transverse sectional view taken on line 3—3 of Fig. 2.

Fig. 4 is a horizontal sectional view taken on line 4—4 of Fig. 2.

Fig. 5 is a view similar to Fig. 4 of the sectional plane being taken on line 5—5 of Fig. 2.

Fig. 6 is an enlarged vertical sectional view taken through one of the intermediate refractory blocks of the lower grate.

Fig. 7 is a perspective view of one of the bottom blocks of the lower grate structures, and

Figs. 8 and 9 are top and bottom perspective views of one of the upper blocks of the lower grate structure.

This application is a division of my co-pending application Serial No. 263,900, filed March 22, 1928.

Referring to the drawings, a furnace 1 is provided with an inclined multiple retort stoker 2 of the underfeed forced draft type. The stoker 2 extends from the front wall (not shown) rearwardly and downwardly between the furnace side walls in the direction of the rear wall (not shown), and terminates in an ash pocket 5, having crushing apparatus 6 located at its lower end.

The stoker 2 comprises broadly a plurality of inclined tuyère chambers or boxes 7, and a corresponding plurality of retorts 8 alternating therewith, constituting an upper grate surface; a plurality of movable extension grate sections 9 disposed in line with the retorts 8, and of sufficient width to extend substantially between the center lines of adjacent tuyère chambers 7; a plurality of extension plates 11 disposed in line with and adjacent to the lower end of the tuyère and retort chambers 7 and 8; a plurality of stationary lower grate sections 13, provided beneath the rearwardly disposed end of the movable extension grate sections 9 and forming a downwardly and forwardly inclined wall portion of the ash pocket 5 extending across the full width thereof; a supporting side plate construction for the foregoing parts including a plurality of steel beams 14 which are integral throughout their length and which extend substantially the full length of the stoker, and bearing means 15 whereby the lower end of the stoker may be afforded an anti-friction support on a main cross girder 16 so that longitudinal expansion and contraction of the stoker 2 may occur. The alternately positioned tuyère and retort chambers 7 and 8 respectively are formed at least in part, by the steel plate beams 14. The bottom of each retort 8 has provided therein a plurality of secondary pushers 126 which extend upwardly in stepped relation from the extension plates 11.

Each of the lower grate sections 13 comprises a rear wall 131, a front wall 132, side walls 133 and 134, a bottom wall 135, and a top wall 136. These walls define an upwardly extending air chamber, or so called grate box, having a lower air inlet opening 137 connected by means of an air duct 138 to a main air chamber 139 positioned directly beneath the tuyère and retort chambers 7 and 8. This upwardly extending air chamber 139 also has a main upper air outlet opening 141 through which the air may pass into a grate chamber 142 formed in each extension grate section 9. The front wall 132 of each lower grate section comprises a main upper plate 143, Figs. 2, 3 and 5, which is mounted on flanges 144 and 145, of vertical angle irons 146 and 147 so as to abut against vertical edges 36 and 39 of the side beams 14, and the vertical extensions 38 respectively. Flanges 148 and 149 of these angle irons 146 and 147 are secured to adjacent tuyère sides 151 of plates 14 of successive tuyère chambers 7. The upper front closure plate 143 is further secured in position by means of angle irons 152 and 153, the flanges 154 and 155 of which are bolted to the

front side of the plate member 143, while flanges 156 and 157 are bolted to the retort sides 37 of the beams 14, and to the adjacent sides of extensions 38 thereof. Filler bars 158 and 159 are positioned between the upper end portions of the flanges 156 and 157 of angle irons 152 and 153, respectively, and the adjacent sides of the beams 14, as shown in Fig. 5. The angle irons 152 and 153 which are positioned in alignment with the 5 retort chambers 8, are relatively short as compared with the angle irons 146 and 147, which are disposed in alignment with the tuyère chamber 7. The pair of angle irons 146 and 147 extend from an upper edge 161 of the front closure 10 plate 143 to a point just above bearing plate 55, while the angle irons 152 and 153 extend from the upper edge 161 of the closure plate 143 to a lower edge 162 thereof. The lower edge 162 of closure plate 143 is spaced from the bearing plate 20 55, as shown in Figs. 1 and 2, so that a desired open space 163 may be obtained. The length of the upper closure plate 143 of each grate section 13 is sufficient to permit vertical edges 164 and 165 thereof to be positioned in substantially the 25 center line of tuyère chamber 7, 7. The upper edge 161 of the closure plate 143 is positioned in desired spaced relation to the upper wall 136 of the grate chamber or box so as to form the air outlet opening 141. In this manner the upper front wall portion of each of the lower grate sections 13 is mounted in position on the lower rear 30 end of the steel supporting beams 14.

The lower open portion 163 of the front wall 132 of each grate section 13 is partially closed 35 by a pair of spaced plate members 166 and 167, Figs. 3 and 4, forming the lower air inlet opening 137, directly in alignment with the retort chamber 8. The plate 166 is mounted on the lower portion of the flange 144 of the angle iron 146, 40 while the plate 167 is similarly mounted on the angle iron 147. Filler strips 168 and 169, Fig. 4, are respectively positioned between the lower portions of the flanges 148 and 149 and the tuyère sides of the plate sections 38. Opposite vertical 45 edges 171 and 172 of the plates 166 and 167 are respectively positioned flush with the edges 164 and 165 of the upper plate member 143, while adjacent spaced edges 173 and 174 are respectively positioned flush with adjacent retort sides of successive plate extensions 38. Upper edges 50 175 and 176 of lower plate members 166 and 167 are positioned in abutting relation to the lower edge 162 of the upper plate 143. Lower edges 177 and 178 are positioned in spaced relation to the bearing plate 55, as shown in Fig. 2.

The lower edge portions of the lower pair of plates 166 and 167 are further supported by means of angle irons 179. Each angle iron 179 extends from the center line of one tuyère chamber 7, to the center line of the next adjacent tuyère chamber as in the case of the upper plate 143. A vertical flange 181 of the horizontal angle iron 179 is secured to an inner side of these edge portions, while a horizontal flange 182 is positioned in spaced relation to the bearing plate 55 of the cross beam 16 to provide a transverse opening 183 extending across the width of the grate section 13. Thus, the lower front wall portion of each of the grate sections 13 is supported on the relatively long angle irons 146 and 147, which, in turn, are secured to the steel side plate construction 14, 38. The vertical meeting edges of successive upper and lower pairs of closure plates 143, 143 and 167, 166 may be closed by means of a vertically extending plate 184, Fig. 5, which is

mounted on a front side of adjacent portions and which extends the full height of the upper and lower closure plates 143 and 166, 167.

Each of the side walls 133, 134 of each lower grate chamber comprises a pair of upper and lower frames 189 and 191 respectively, which are mounted directly in the center line of the tuyère chamber 7 over the meeting edges of successive pairs of upper and lower rear wall closure plates 143, 143 and 166, 167. These plates constitute a 10 common wall for successive pairs of lower stationary grate sections 13. The upper plate frame 189 is provided with transversely extending spaced feet 192 which are bolted to the upper plate member 143. The lower grate frame 191 is also provided with transversely extending feet 193 and 194 which are respectively bolted to the upper plate 143 and to the vertical flange 181 of the horizontal angle iron section 179. The upper and lower members 189 and 191 are slightly spaced to provide a relatively small air passage 195 therebetween. The upper grate frame 189 is provided with an upwardly projecting portion 196 having a beveled front edge 197, Figs. 1 and 2, extending downwardly and forwardly to the 25 upper supporting foot 192.

The rear wall 131 of each grate section 13 comprises a plurality of grate blocks 198 which are disposed in side by side, as well as superimposed relation forming horizontal and vertical rows. Each vertical row comprises a lower main supporting grate block 199, a plurality of intermediate grate blocks 201, and an upper grate block cap 202. As shown more particularly in Figs. 1 to 3, and 6, each intermediate grate block 30 201 comprises a rear wall 213 and side walls 214 and 215. The rear wall 213 is provided with an upper vertical surface portion 216 and a lower, forwardly and downwardly inclined surface portion 217. The surface portions 216 and 217 constitute ash abutting surfaces which are directly exposed to the furnace heat. The upper surface portion 216 is forwardly offset with respect to the adjacent inclined lower portion 217 of the preceding grate block 201. In this manner a lower edge 218 of the rear wall 213 of one grate block 40 201 overhangs an upper edge 219 of the wall 213 of the next grate block directly below the same, thereby providing a plurality of overhanging shoulder portions that are so positioned as to prevent the lodging of refuse material thereon. 45

The side wall 214 is provided with a plurality of air deflecting ribs 220 that abut against air deflecting ribs 221 of the opposite wall 215 of the next adjacent grate block 201. The grate blocks 199 are provided with similar ribs, as 50 shown in Fig. 7. These ribs extend forwardly and downwardly from the rear wall of the grate blocks and terminate in substantially horizontally extending front and end portions 222. Thus, the adjacent side walls of the grate blocks 201, 201 and 199, 199 are maintained in desired spaced relation, and a plurality of air outlet passages 223 are also formed which extend forwardly and upwardly in a direction substantially 55 opposite to that of the downwardly moving material in the ash pocket 5. An advantage of discharging the air in this manner is that it causes a more complete burning of such combustible as still remains in the refuse in the ash pocket 5. 60 The air may be supplied to the air passages 223 from the air chamber of the lower grate section 13 through a plurality of apertures 224, Figs. 6 and 7, positioned forwardly of the air passages 223 in the side walls of the grate blocks. A plu- 65 70 75 75

arity of spaced heat radiating ribs 225 extend forwardly from an inner side 226 of the rear wall of each of the grate blocks 199 and 201, each rib being triangular in cross section and extending substantially the full length of the grate block. The inner upper edges 227 of the rear and side walls of blocks 199 and 201 may be beveled as shown in Figs. 6 and 7.

The front edge of the grate block side wall 214 terminates in a pair of spaced locking lugs 228, while the side wall 215 terminates in a pair of spaced locking lugs 229. The upper and lower locking lugs 228, 229 for the side wall 214 are respectively provided with vertical recesses 232 and 233 adapted to receive portions 234 and 235 of flanges 236 and 237 extending inwardly of the grate section 13 from a rear edge portion 238 of the upper plate frame 189. The upper plate member 189 is provided with a relatively short flange 241 in addition to the flanges 236 and 237, the former corresponding in dimension to either of the flange portions 234 or 235. The length of the flange portions 234 and 235 is such as to permit the disengagement of the pair of lugs 228, 229 from the plate member 189 upon a relatively slight vertical movement. The lower plate frame 191 is provided with a locking flange 242 corresponding to the flanges 236 and 237, and a relatively long flange 243 for reasons as will presently appear. The plate frames 189 and 191 are also provided with locking flange portions 239 which are similar to the flange portions just described, but extend in the opposite direction thereto inwardly of the next adjacent grate section 13.

The upper and lower locking lugs 229, 229 of the other side wall 215 of the intermediate grate block 201 is provided with a pair of recesses 245, 245; which coact with locking flanges 246 corresponding in all respects, to the flanges 236 and 237, 242 and 243, just described, for the plate frames 189 and 191. The flanges 246 extend transversely of a pair of upper and lower plate frames 247 and 248, respectively. The frames 247 and 248 are respectively bolted on the upper plate member 143, and the horizontal angle-iron 179 respectively. The pairs of plates 189, 191 and 247, 248 thus provide detachable mountings for the intermediate grate blocks 201 in a vertical row immediately adjacent one side of the grate sections 13.

The next vertical row of grate blocks is similarly secured to the spaced pairs of frames 247, 248 and 249, 250, each frame having inwardly extending locking flanges 251, Fig. 5, coacting with the locking lugs of the intermediate grate blocks 201 so as to permit detachment upon a relatively small vertical movement. The dimension of the grate sections 13 is such that the plate frames 249, 250 are substantially in alignment with the center line of the retort chamber 8. The next vertical row of grate blocks is supported by the plate frames 249, 250 and 252, 253, while the side vertical row is supported on the plate frames 250, 253 and 254, 255. The frames 254, 255 constitute at least a portion of the side wall 134 of the lower grate chamber that is opposite to the side wall 133.

The lower, supporting grate block 199 of each vertical column is shown in vertical section in Fig. 2, and in perspective in Fig. 7. The lower grate block 199 is constructed substantially the same as the intermediate grate blocks 201, with the exception that a lower pair of lugs 256, 256, which are respectively mounted on side walls 257, 257, are provided with recesses 257 which are some-

what deeper than the recesses of the upper pair of lugs. This lower pair of recesses 257 are closed at their upper ends by supporting walls 258 which engage shoulders 259, formed by enlarging or widening the lower end portion of the flange 243 of each lower frame plate, as shown in Fig. 2. The lower grate block 199 of each vertical column is thus hung or directly supported on the lower end portions of a pair of lower grate-plate frames, while the weight of the remaining grate blocks in each row is directly carried by the lower grate block. The dimension of these locking flanges and recess portions is such that the lower grate block 199 may also be moved rearwardly away from the lower grate frames upon a relatively small vertical movement thereof.

A rear wall 260 of each of the lower grate blocks 199 is provided with a flange portion 261 that extends below the lower edges of the grate-block side walls 257, 257. An outer side 262 of the flange 261 is positioned in alignment with the beveled or inclined surface portion 217, while an inner side is provided with an oppositely beveled surface portion 263 adapted to abut against a complementary rear edge portion 264 of a plate member 265, Fig. 2, constituting the bottom wall 135 of the grate chamber. The upper portion of the inclined wall 263 is provided with a shoulder 266 which is supported on an upper side 267 of the plate member 265, thereby providing a further secondary mounting for the lower grate blocks 199.

It is noted that the vertical rows of the grate blocks define an approximately flat surface that is exposed to the heated ashes in the pocket 5, and that this surface is inclined downwardly and forwardly, so that an ash pocket of increasing cross-sectional area may be obtained as the ashes are removed in the direction of crusher apparatus 6 positioned at the bottom of the ash pocket 5, Fig. 1. Moreover, a plurality of air-outlet openings in this exposed surface are provided between successive vertical rows of grate blocks, the air being deflected as it passes into the ash pocket 5 forwardly and upwardly in a direction opposite to that of the downwardly moving refuse. Furthermore, the several grate blocks, being secured in position without the use of bolts or rivets, may be readily renewed merely by first moving the grate block a relatively small vertical distance, and then further moving said grate block rearwardly and outwardly of the lower-grate structure.

The lower edge 407 of each of the front walls 327 of the grate-guard sections is in spaced relation to the top edge of the upper intermediate grate blocks 201, permitting the mounting therebetween of a rear wall 414 of the upper grate-block caps 202. The width of each of the grate-block caps 202 is substantially equal to that of the intermediate grate blocks 201 and they are so positioned as to constitute continuations of the vertical rows of grate blocks 201 that extend upwardly from the lower grate block 199. Each of the grate-block caps 202 comprises, in addition to the flat rear wall 414, a pair of forwardly extending side walls 415 and 416, as shown in the perspective views of Figs. 8 and 9.

A lower edge 417 of the rear wall 414, Fig. 2, is mounted on an adjacent upper edge of the intermediate grate-block 201, and slightly overhangs the adjacent, exposed face portion 216 thereof, as in the case of the intermediate grate-blocks 201. Edges 418 of the side walls 415, 416 are similarly mounted on upper edges of the

grate-block side walls 214, 215, respectively. Each of the side walls 415, 416 is provided with a pair of spaced projecting lugs 419 and 421, of which the lug 419, immediately adjacent to the rear wall 414, is the shorter. These lugs extend beyond the edges 418 of the side walls 415, 416 and abut against the inner, upper side portions of the adjacent side walls 214, 215 of the intermediate grate-block 201. In this manner, transverse movement of the grate-block cap 202 relative to the lower, supporting grate-block 201 is prevented. The rear pair of locking lugs 419 are relatively shorter than the front pair of locking lugs 421 in order to decrease the upward tilting movement necessary in order to clear the lugs 219 of the rear wall 213 of the supporting grate-block 201.

Each of the side walls 415, 416 is provided with an angled rib 422 which abuts against the adjacent rib of the next grate-block cap 202, thereby forming therebetween an air passage. The inclination of the rib is such that air may be deflected outwardly and upwardly, as in the case of the lower air passages 223. Air may be supplied to the passages formed by the ribs 422, by reason of the presence of air-outlet openings 423 in front portions of the side walls 415, 416. A front side of the rear wall 414 is provided with a plurality of forwardly-extending tapered ribs 424, corresponding to the radiating ribs 225 of the lower grate-blocks.

An upper horizontal wall 425 of each of the grate-block caps 202 is positioned just below the lower edge 407 of an adjacent grate-guard front wall 327, and it extends forwardly to an upstanding cross-flange 426. The flange 426, Figs. 8 and 9, extends across the full width of the rear wall 414 and slightly beyond the same at each side to provide overhanging shoulder portions, outer sides 427 and 428 which are positioned respectively in the plane of the outer side of the air-deflecting ribs 422.

A rear side 429 of the upright cross-flange 426 is positioned immediately adjacent to the front side portion 408 of the grate-guard section front wall 327, thereby preventing a rearward movement of the cap 202. An upper horizontal edge 431 of the cross-flange 426 is positioned in abutting relation to the edges 405 and 406 of the spaced locking lugs 400, 401 and 395, 396, respectively, thereby preventing an undesirable upward movement of the grate-block cap 202. The top wall of the grate-block cap 202 may be further extended forwardly and downwardly by means of a curved portion 432, opposite edges of which are positioned in substantial alignment with the opposite edges 427 of the upright flange 426. These edge portions abut against the adjacent edge portions of successive grate caps 202, forming air chambers between successive pairs of side walls 415 and 416 having a rear outlet only into the ash pocket 5. A central lower edge portion of the curved wall 432 may be recessed as shown in Fig. 8.

Assuming, for example, that it is desired to replace the lower, supporting grate-block 199 in the vertical row shown in Fig. 2, the locking key associated with the grate-guard section 322 is first removed. This permits the removal of the guard plate member 324. The guard plate member 324, which prevents the rearward and upward movement of the grate-block cap 202, having been removed, the latter may be lifted vertically, disengaging the pair of lugs 419, 421 from the adjacent intermediate grate-block 201, and

then rearwardly away from the lower grate structure.

Should it not be desirable to remove entirely the guard plate member 324, the latter is lifted just sufficiently to permit the locking cross-flange 426 to clear the adjacent lower edge 407 of the grate-guard front wall 327, whereupon the cap 202 is tilted slightly until the front pair of lugs 419 are above the adjacent upper edge of the rear wall of the supporting grate-block 201. The cap 202 is then moved upwardly and rearwardly from the grate structure. The remaining intermediate grate-blocks 201 may be detached from the supporting lugs on the grate-plate frames by moving the same vertically until the lugs are detached, and then rearwardly. When the lower, supporting grate-block 199 is reached, it may be removed in a similar manner and then replaced by a new grate block. The parts may be again replaced in the reverse order of their removal.

While the grate blocks herein described are admirably adapted to fulfill the objects primarily stated, it is to be understood that the invention is not to be limited thereto, since they may be embodied in other forms, all coming within the scope of claims which follow.

What is claimed is:

1. A block for a grate structure, comprising top, side and rear walls, each of said side walls having provided toward the front end thereof a substantially arcuate flange, a transverse flange extending upwardly from said top wall, a series of cooling fins extending forwardly from the front surface of said rear wall, and one or more projections depending from the lower inner surface of each of said side walls.

2. A grate block for a stoker structure comprising top, side and rear walls, a laterally extending arcuate flange provided along the top and front edges of each of said side walls, a transverse flange extending upwardly from said top wall, cooling fins provided on the inner surface of said top and rear walls, and means extending laterally from the outer surface of said side walls defining passages for draft air.

3. A grate block of the class described, comprising a substantially vertical rear wall and substantially vertical side walls arranged at an angle to said rear wall, a plurality of substantially vertical fins projecting forwardly from the front surface of said rear wall, a series of ribs extending laterally from the outer surface of each of said side walls defining passages for draft air, and locking lugs mounted on the front edge of each of said side walls.

4. A block for a lower grate structure comprising top, side and rear walls, a substantially arcuate flange provided on each of said side walls, a transverse flange extending upwardly from said top wall, a series of cooling fins extending forwardly from the front surface of said rear wall, and locking means provided on each of said side walls.

5. A grate block of the class described, comprising a substantially vertical rear wall, and substantially vertical side walls disposed at an angle to said rear wall, a plurality of substantially vertical fins projecting forwardly from the front surface of said rear wall, a series of ribs extending laterally from the outer surface of each of said side walls defining passages for draft air, locking lugs mounted on the front edge of each of said side walls, and an extension for said rear

wall extending below the lower edges of said side walls.

6. A grate block of the class described, comprising a substantially vertical rear wall, and substantially vertical side walls disposed at an angle to said rear wall, a plurality of substantially vertical fins projecting forwardly from the front surface of said rear wall, a series of ribs extending laterally from the outer surface of each of said side walls defining passages for draft air, locking lugs mounted on the front edge of each of said side walls, and means providing angularly disposed surfaces on said rear wall.

7. A grate block adapted to comprise one of a series arranged in side by side relation in a lower grate structure of a stoker furnace, said grate block comprising a substantially vertical rear wall and a pair of laterally spaced substantially vertical side walls, a plurality of cooling fins extending forwardly from the front surface of said rear wall, means at the sides of said grate block for maintaining the same in spaced relation with adjacent grate blocks, and locking lugs provided on each of said side walls for detachably securing said grate block in position.

8. A grate block for a lower grate structure of a stoker furnace, comprising a substantially vertical rear wall, and a pair of laterally spaced, substantially vertical side walls, a plurality of cooling fins extending forwardly from the front surface of said rear wall, ribs extending laterally from the outer surface of each of said side walls defining passages for draft air, and locking lugs provided on each of said side walls for detachably securing said grate block in position.

9. A grate block adapted to comprise one of a series arranged in side by side relation in a lower grate structure of a stoker furnace, said grate block comprising a substantially vertical rear wall, and a pair of laterally spaced substantially vertical side walls, each of said side walls having one or more apertures provided therein through which draft air may pass, a plurality of cooling fins extending forwardly from the front

surface of said rear wall, means at the sides of said grate block for maintaining the same in spaced relation with adjacent grate blocks, and locking lugs provided on each of said side walls for securing said grate block in position.

10. A grate block for a lower grate structure of a stoker furnace, comprising a substantially vertical rear wall, and a pair of laterally spaced, substantially vertical side walls, each of said side walls having one or more apertures provided therein through which draft air may pass, ribs projecting outwardly from each of said side walls defining passages for draft air, a plurality of cooling fins extending forwardly from the front surface of said rear wall, and locking lugs provided on each of said side walls for securing said grate block in position.

11. A grate block of substantially U-shaped form, having a pair of vertically disposed legs integrally connected at one end thereof to a substantially vertical web, each of said legs having one or more apertures provided therein through which draft air may pass, a plurality of substantially vertical fins projecting from one face of said web, ribs projecting outwardly from each of said legs defining passages for draft air, and locking means provided on each of said legs for securing the grate block in position.

12. A grate block adapted to comprise one of a series in a lower grate structure of a stoker furnace, said grate block comprising a substantially vertical, rearwardly disposed wall, and a pair of side walls integral with and extending forwardly of the side edges of said rearwardly disposed wall, each of said side walls having one or more apertures provided therein through which draft air may pass, cooling fins secured to and extending forwardly of said rearwardly disposed wall, ribs projecting outwardly from each of said side walls defining passages for draft air, and means provided on said side walls for securing said grate block in position.

HERBERT E. PRESTON,
